UNITED STATES PATENT OFFICE.

WILLIAM R. NICOLL, OF OWATONNA, MINNESOTA, ASSIGNOR TO MINNETONNA COMPANY, OF OWATONNA, MINNESOTA, A CORPORATION OF MINNESOTA.

BUTTER-MAKING MACHINE.

1,183,104.

Specification of Letters Patent.

Patented May 16, 1916.

Application filed May 7, 1915. Serial No. 26,466.

To all whom it may concern:

Be it known that I, WILLIAM R. NICOLL, a citizen of the United States, residing at Owatonna, in the county of Steele and State 5 of Minnesota, have invented certain new and useful Improvements in Butter-Making Machines, of which the following is a specification.

This invention relates to butter making 10 machines, and more particularly to an adjustable basket for use in connection with such machines, which is adjustable for the purpose of increasing the efficiency of the machine in working batches of different 15 sizes therein.

The invention consists in the novel construction, combination and arrangement of the several parts.

In the drawing, Figure 1 is a sectional 20 view showing a butter making machine having an adjustable basket, Fig. 2 is a perspective of the basket, and Fig. 3 is a longitudinal section of the machine supported in bearing standards.

25 In butter making machines it has been found that batches of different sizes are worked with greater efficiency if the cradle or basket which raises the material in the machine as it rotates, is placed at certain 30 distances from the butter working roller with which it coöperates. For example, if a small batch is to be worked it can be worked with greater efficiency if the basket is near the roller, and to work a larger batch 35 the basket is moved to some distance away from the roller. By this construction it is possible to increase the efficiency of a machine for working batches of different sizes and it is possible to materially cut down the 40 number of sizes of machines necessary to provide a complete manufacturer's line.

Referring now more particularly to the drawing, the numeral 1 designates generally the receptacle or drum of a butter making machine, shown substantially circular in Fig. 1, although it may be of any desired shape. This drum is formed with a door opening 2 extending lengthwise of the drum, and the drum is intended to rotate 45 about a central axis. Mounted eccentrically in the drum is a butter working roller 3 which is rotated in the ordinary manner by means not shown in the drawing. The door opening is formed by means of sills 4 which

extend inwardly to provide a shoulder 5 55 at one side thereof. Adjacent the center of the drum at each end thereof is an inwardly projecting pin or projection 7. An adjustable basket is mounted between the projections 7 and one of the door-sills 4 and comprises end pieces 8, preferably constructed of metal and each formed at one end with a plurality of slots 9 which are adapted to engage the projection 7 at one end of the drum. At the other end it is formed with 60 an offset projection 10 which is adapted to engage the shoulder 5 of the sill 4. Extending between the two end pieces and connected thereto are slats 11 suitably spaced apart, and a roller 12 at the slotted end of the basket. Pivoted to the slat nearest the projections 10 is a latch 12' which is adapted to engage the lower side of one of the sills 4 and to hold the outer end of the basket 65 against the shoulder 5 regardless of the adjusted position of the inner end of the basket. A door 13 is provided to fit the opening 2 and it preferably extends the full length of the drum.

From this description it will be seen that 70 this basket is not only adjustable but it is easily removable from the drum. It is only necessary to rotate the latch 12' to loosen the outer end of the basket from its engagement with the wall of the drum whereupon 75 the basket can be swung outwardly away from the shoulder 5, after the door 13 is removed, and lifted outwardly from engagement with the projections 7. Thus it is 80 easily removable for cleaning or can be 85 easily adjusted by simply engaging the projection 7 with another set of slots 9. Although only two slots 9 are shown in the present exemplification of the invention, it is obvious, of course, that a greater number 90 of slots may be used, thus increasing the number of positions at which the basket will be placed, and thereby increasing the efficiency of operation for a greater number of batches of different sizes.

100

What I claim is:

1. A butter making machine comprising a drum and a basket adapted to be inserted therein having one end supported by the inner wall of the drum, and means for supporting the other end of the drum adjacent the center thereof.
2. A butter making machine comprising

a drum, a basket adapted to be inserted in the drum having one end supported by the inner wall of the drum, and means at the other end of the basket for adjustably supporting and positioning the basket adjacent the center of the drum.

3. In a butter making machine, the combination with a drum, of a basket adapted to be inserted therein having one extremity in contact with the inside of the outer wall of the drum and slots in the other extremity, and a support in connection with each end of the drum adjacent the center thereof to engage corresponding slots of the basket to hold it adjustably in any one of a plurality of positions.

4. In a butter making machine, the combination with a drum having inside end projections and a basket having slots at one end thereof adapted to engage the projections to hold the inner end in a plurality of positions, and means at the other end of the basket to engage the inside of the outer wall of the drum.

5. In a butter making machine, the combination with a drum having inside end projections and a basket having slots at one end thereof adapted to engage the projections to hold the inner end in a plurality of positions, means comprising a shoulder on the inside of the outer wall of the drum to engage the inner end of the basket, and a latch on the basket to hold this end in engagement with the shoulder.

6. In a butter making machine, the combination with a drum having inside end projections adjacent the center, of a basket having side pieces with slots at the inner ends to engage the projections for holding the inner end of a basket in a plurality of places, and means at the outer end of the basket to hold it in a fixed position with respect to the outer wall of the drum.

7. In a butter making machine, the combination with a drum having inside end projections adjacent the center and a shoulder on the inside of the outer wall of the drum, of a basket comprising side pieces, each of which is formed with slots to engage one of the said projections at the end of the drum and the other end being adapted to engage the shoulder of the drum, and a latch pivotally connected to the basket and movable to engage the wall of the drum to hold the outer ends of the end pieces in engagement with the shoulder of the drum irrespective of the inner adjusted position of the basket.

8. In a butter making machine, the combination with a drum having a door opening in the outer wall thereof and having inside end projections adjacent the center, and an adjustable basket having means at the inner end for engaging the said projections and having extremities at the other end which engage one side of the door opening,

and a door fitting the opening extending the length of the drum the basket being bodily removable and adjustable through said opening.

9. In a butter making machine, the combination with a drum having a door opening in the outer wall and inside end projections adjacent the center, of an adjustable basket having slotted inner ends to engage the projections and outer extremities which bear against one side of the door opening, a latch in connection with the basket to hold the inner end thereof in engagement with one side of the door opening, and a door fitting the opening extending the full length of the drum the basket being bodily removable through said opening.

10. In a butter making machine, the combination with a drum, of a basket having one end in fixed engagement with the inside of the outer wall of the drum, and means to adjustably hold the other end in a plurality of positions adjacent the center of the drum.

11. In a butter making machine, a drum having a central axis of rotation, a butter working roller mounted therein, and a basket fixed at its outer end in the inside of the outer wall of the drum and adjustable at its inner end toward and from the butter working roller.

12. In a butter making machine, a drum, a butter working roller mounted therein, a removable basket adjustable in the drum having its outer end in fixed engagement with the drum, and means for holding the inner end of the basket at different distances from the butter working roller.

13. In a butter making machine, a drum rotatable about a central axis, a butter working roller eccentrically mounted therein, and a basket extending substantially in a radial direction from the center of the drum having its outer end fixed with respect to the drum and its inner end adjustably mounted with respect to the butter working roller.

14. In a butter making machine, a drum rotatable about a central axis, a butter working roller eccentrically mounted therein, and a basket extending substantially at right angles to the plane joining the axes of the drum and the roller fixed at its outer end to the drum and adjustable at its inner end to vary the distance between it and the roller.

15. In a butter making machine, the combination with a drum, of a butter working roller mounted therein, the drum having a door opening extending parallel with the roller, a basket having one end in engagement with one side of the door opening and means for holding it in this position, said basket extending toward the butter working roller, and means at the inner end of the basket for holding it in adjustable position with respect to the roller.

16. An adjustable basket for a butter mak-

ing machine, comprising end pieces each with a plurality of slots at one end and an offset projection at the other, slats connected to the end pieces, and a latch in connection with the slat at the end adjacent the said offset projections.

In testimony whereof I have signed my

name to this specification, in the presence of two subscribing witnesses, on this 3rd day of May A. D. 1915.
